CAR END

William D. Thompson, Birmingham, Mich., assignor, by mesne assignments, to Standard Railway Equipment Manufacturing Company, a corporation of Delaware.

Application March 14, 1938, Serial No. 195,872

4 Claims. (Cl. 105—410)

The invention relates to car wall constructions being a continuation in part of my copending application for patent, Serial No. 760,006, filed December 31, 1934. The subject matter of the parent application is a railway freight car of the house type in which the vertical walls and also the roof are formed of channel plate units, and preferably units fashioned by a rolling process. Such units have various advantages, particularly where formed by the cold rolling process which densifies the metal, increasing its strength and the smoothness of surface. They can also be manufactured more economically and can be readily secured to each other and to cooperating elements by welding. The present application relates to the car wall construction and more particularly to car ends.

It is the primary object of the invention to obtain increased strength, more particularly for withstanding stresses developed by the shifting of the load to impinge against the end of the car, and also to stresses due to any external end shocks. In the present state of the art, certain constructions of car ends have been formed of metal plates which are variously ribbed or fashioned to produce a trussing effect and which at their margins are secured to the end posts and end sills of the car. A point of weakness with many of such constructions is that the marginal portions of the plates are merged into a single plane for attachment to the posts and sills. Thus where there is an end shock either external or internal these single plane portions are easily deflected, producing a bulging or other distortion of the car end. It is a primary object of the present invention to overcome such defect by a more rigid attachment between the car end and the body of the car. It is a further object to attain a construction which is formed from rolled stock, thereby dispensing with the use of costly dies and presses and also securing greater strength in the material itself. Still further, it is an object to attain a construction which will resist end shocks, whether these be from the inside in an outward direction or from the outside in an inward direction. With these and other advantages in view the invention consists in the construction as hereinafter set forth.

50 In the drawings:

Figure 1 is an end elevation of a railway freight car to which my improved end construction is applied;

Figure 2 is a side elevation of the end portion 55 of the car;

Figure 3 is a vertical section through the car end;

Figure 4 is a plan view thereof partly in horizontal section;

Figure 5 is a perspective view of a portion of the end showing the attachment to a modified construction of corner post for the car;

Figure 6 is an elevation of the blank from which the end plate is formed;

Figure 7 is a horizontal section showing the car end as attached to another modified construction of corner post;

Figure 8 is a perspective view of the reinforcing bracket used in Figure 7;

Figure 9 is an end elevation of the construction in Figure 7.

My improved car end A may be formed either of a single unit or preferably of a series of units secured to each other by welding. As shown in Figures 1 to 4, inclusive, the end is formed of a series of three units A', A² and A³, each of which is a reversely channelled plate comprising portions alternately in spaced parallel planes connected by portions substantially normal to these planes. Each unit also has one or more complete channels in the central part thereof and marginal portions which are complementary to each other to form another channel. Thus by abutting the edges of these units at B and B' and welding them together, there is formed an integral structure extending from floor sill to roof and with the channels thereof extending from side to side. This end unit may be secured to the car body in various ways. Thus as shown in Figures 1 to 4, metallic strips C are notched to correspond in contour to the reverse channels and are secured by welding to the ends of said channel portions on opposite sides of the car. These strips extend inward or in the longitudinal direction of the car to overlap the side walls D and corner posts E of the car to which they are attached either by riveting or welding. In the modification shown in Figure 5, instead of securing the ends to separate strips they are directly attached to the corner posts E' which as shown are of an angle cross section. The ends of the channels abut against the flange E² of the post and are rigidly secured thereto by welding, preferably the full length of contact. They are also further attached to the member E' by welding both edges of the inner panel to the flange E³ of the post.

This forms an exceedingly rigid connection for resisting end shocks and one which will not tend to either twist or distort the post. Inasmuch as the angle members E' which form the corner posts

are rolled sections they have fillets at the inner corners thereof. Thus if the ends of the channel portions were square they would be held by these fillets from full contact with the flange E^2 . This 5 may be avoided by forming the channel units from blanks such as shown at F, Figure 6, having the portions which form the inner plane portions of the car end cut away at F' to leave the intermediate portions F^2 of a slightly greater length. 10 Such blank when formed into the channel section will abut against the flange E^2 all of the portion F^2 which constitutes both the outer plane portion and the portions normal thereto. 15 The constructions thus far described require the car end to extend the full width of the car between the outer sheathing thereof. In the construction of Figures 7 to 9 inclusive, the corner posts G are of a Z-bar cross section with the intermediate web G' thereof extending inward 20 or transverse to the length of the car. This forms inner flanges G^2 on the post which are spaced from each other by a dimension less than the full width of the car and between which flanges the car end is placed. The channel portions are welded to these flanges G^2 in a similar manner to that previously described in connection with Figure 5. This construction by reducing the width of the car end saves in weight but as thus far described is open to the 25 objection that it is less rigid to withstand end stresses. For instance, an outward stress in the car end occasioned by the shifting of the load inside the car thereagainst would tend to bend the web portions G' of the posts outward, or to 30 enlarge the angle between the same and the flanges G^2 . On the other hand, inwardly directed shocks against the car end would tend to bend the web portions G' in an inward direction, thereby diminishing the angle between the same 35 and the flanges G^2 . Both such deflections can be prevented by reinforcements, such as the corner brackets H illustrated in Figures 7 to 9. These brackets may, if desired, be formed of 40 pressed sheet metal of a channel section, as illustrated in Figure 8, having a generally triangular form with the edges H' and H^2 abutting against the flange G^2 and web G' , and secured thereto by welding. If desired, one of 45 these brackets may be placed adjacent to each of the outer plane portions of the end and will have the effect of thoroughly bracing the structure against endwise displacement. Thus, if the 50 shock is from the load inside and in an outward direction, then the members H will act as tension members holding the angle between the web G' and flange G^2 constant, and thereby preventing any outward movement of the end. On 55 the other hand, if the shock against the end is in an inward direction the members H will act as compression members which again will hold the angle between the web G' and flange G^2 constant, thereby preventing inward movement of the end. The added weight of these bracket members H will be considerably less than the 60 weight saved by reducing the width of the car end, so that the construction illustrated in Figures 7 to 9 will be less in total weight than that illustrated in the other figures.

A characteristic feature of all of the modifica-

tions above described is that there are no lines of weakness between the car ends and the car body as is the case with such constructions where the reinforcing ribs merge into a common plane at the margin of the sheets. Consequently, 5 these constructions are all much more rigid in withstanding deflections longitudinally of the car in either an outward or an inward direction. This increase in rigidity is due in part to the fact that both the outer and inner planes of the 10 channeled members extend in straight lines from post to post and together with the latter form a truss. Also, the channeled members in both the spaced planes and the planes normal thereto are welded to the post members throughout 15 their entire cross sectional contour, which further increases the rigidity.

What I claim as my invention is:

1. In a railway car, a combination of spaced apart corner posts each having a flat portion in 20 a plane extending longitudinally of the car and an angle portion transverse thereto, and a car end having inner and outer plane portions with intermediate connecting portions substantially normal thereto together forming channel portions 25 extending transversely of the car, the ends of said channel portions abutting against said flat portions of the posts and welded thereto, and said channel portions being also welded to the angle portions of said posts extending transversely of the car.

2. In a railway car, the combination with a corner post of angle cross section having a fillet in the angle thereof, of a car end having inner and outer plane portions with intermediate connecting portions substantially normal thereto together forming channel portions of uniform cross section throughout their length, the ends of 35 said channel portions being cut away to clear said fillet and to permit all portions of the edges 40 thereof to abut against one flange of said corner post, said edges throughout their length being welded to said flange and said channel portions being also welded to the other flange of said angle post.

3. In a railway car, the combination of spaced apart corner posts each having a flat portion in 45 a plane extending longitudinally of the car and an angle portion transverse thereto, and a car end having inner and outer plane portions with 50 intermediate connecting portions together forming channel portions extending transversely of the car, the ends of said channel portions abutting against said flat portions of the posts and welded thereto, and said channel portions being 55 also welded to the angle portion of said posts extending transversely of the car.

4. In a railway car, the combination with a corner post of angle cross section having a fillet in the angle thereof, of a car end having inner 60 and outer plane portions with intermediate connecting portions, the ends of said channel portions being cut away to clear said fillet and to permit all portions of the edges thereof to abut against one flange of said corner post, said edges 65 throughout their length being welded to said flange and said channel portions being also welded to the other flange of said angle post.

WILLIAM D. THOMPSON.
